[57] CLAIM

The ornamental design for a combined mobile imaging and scanning machine for radiation detection, as substantially shown and described.

DESCRIPTION

FIG. 1 is a front elevational view of a combined mobile imaging and scanning machine for radiation detection showing my new design and the rear side is identical; FIG. 2 is a top plan view thereof; FIG. 3 is a left side elevational view thereof; FIG. 4 is a right side elevational view thereof; FIG. 5 is a bottom plan view thereof; and FIG. 6 is a perspective view of a combined mobile imaging and scanning machine for radiation detection in operation.
